UNITED STATES PATENT OFFICE.

JAMES C. CHAMBERS, OF ST. LOUIS, MISSOURI.

MOTION-PICTURE-PROJECTING MACHINE.

1,300,247.

Specification of Letters Patent. Patented Apr. 15, 1919.

Application filed August 29, 1918. Serial No. 251,919.

To all whom it may concern:

Be it known that I, JAMES C. CHAMBERS, a citizen of the United States, residing at St. Louis, State of Missouri, have invented 5 certain new and useful Improvements in Motion - Picture - Projecting Machines, of which the following is a full, clear, and exact description, reference being had to the accompanying drawings, forming a part 10 hereof.

The present improvement is directed to motion picture projecting machines, these pictures as well understood in the art, being carried on films of highly inflammable 15 material. To secure the projection of the pictures a powerful light is necessary, the heat generated by the light being sufficient to ignite the film should the movement of the latter be arrested for any appreciable length 20 of time during the normal operation of the machine. The object of the present invention is to provide suitable means for automatically cutting off or intercepting the light rays in the event that the film becomes 25 in any way disarranged or tangled, or its speed of advance slackened or arrested, thereby saving the film from destruction. As well understood in the art, the film 30 winds on one reel and unwinds from another, and is under tension while in service or in motion. In the present embodiment of my invention this tension is availed of to control not only the action of the light shield or cut-off, but the action of the contacts or wipers which close the circuit of the 35 electric current operating the motor by which the film is propelled. When anything therefore happens to the film which tends to remove the tension under which the 40 same operates under normal service conditions, the light shield or cut-off instantly asserts itself and the light rays are intercepted so that the film can not take fire. The 45 advantages of the invention will be fully apparent from the following detailed description in connection with the accompanying drawings in which—

Figure 1 represents a side elevation of a conventional motion picture projecting machine showing my invention applied thereto; Fig. 2 is an enlarged side elevation of the bottom set of connections entering into construction of the light-shield controlling mechanism; Fig. 3 is an inside end elevation of the sprocket and guide spools, showing the shutter or cover plate for closing the

slot traversed by the oscillating spindle of the sprocket spool; Fig. 4 is a vertical cross-sectional detail on the line 4—4 of Fig. 2; Fig. 5 is a horizontal section on the zig-zag 60 line 5—5 of Fig. 2; Fig. 6 is an enlarged side elevational detail of the drop-lever and the shield or cut-off suspended therefrom; Fig. 7 is an end view of Fig. 6; Fig. 8 is a horizontal cross-sectional detail on the line 65 8—8 of Fig. 6; Fig. 9 is a detached perspective of the wiper plate carried by the oscillating angle-bracket to which the weighted tripping arm or lever is secured; and Fig. 10 is a vertical sectional detail on 70 the line 10—10 of Fig. 5.

Referring to the drawings, L, represents a projecting lantern, H, the motion-head or film-advancing mechanism operated by the electric motor M, the film *a* unwinding from a reel or spindle in the magazine A, and winding on a reel or spindle in the magazine A', motion being imparted to the film and to the reels by mechanism well known in the art and shown more or less conventionally in the drawings. The film in its 80 passage from the unwinding to the winding reel is maintained taut, sufficient tension being imposed thereon to preserve uniformity of speed and positiveness of travel and prevent clogging or congestion. The tension or tautness of the film is availed of under my invention to bring about the proper control of the mechanism by which the light-shield or cut-off is actuated with any change or relaxation of said tension. My invention has for its object to cut off the light (and heat) rays while the motion head is in operation and under circumstances where the film may accidentally tear or its travel becomes arrested or is continued from the unwinding reel without correspondingly wrapping on the winding reel; and in general in cases where the tension or tautness of the film is for any reason relaxed. In the present embodiment 90 of my invention I secure to the outer wall of the magazine A' a plate or mounting 1, said plate being provided with a stationary spindle or screw-bolt 2 over whose inner threaded portion is loosely passed the guide spool 3 105 maintained in proper position on the bolt by the nut *n*. The outer smooth or unthreaded portion of the bolt 2 supports an oscillating angle-bracket 4, the arm of the bracket traversed by the bolt being formed with an enlarged head *h* for the accommodation of the bolt. The head *h* is provided with a screw-

socket for attaching an arm 5 serving as a tripping lever, said arm being provided with a weight W which may be adjusted to any desired position on the arm. Leading from the corner of the bracket 4 and projecting inwardly into the magazine A' through a curved elongated slot e in the plate 1 and magazine wall, is a stem or spindle 6 on which is mounted the sprocket spool 7, the film a passing over the spool 7 and under the guide spool 3 as shown (Fig. 2). To keep the slot e permanently covered (so as to protect the film on the inside from extraneous influences) I pass over the members 2 and 6 a shutter or cover plate 8, which is maintained in engagement with the inner face of the magazine wall by the spool 3. The axis of the spindle 6 is substantially coincident with the axis of the outwardly projecting arm of the angle bracket 4, that is to say, the arm disposed at right angles to the plate 1. To the free end of this arm is pivotally secured one end of a vertically oscillating block or short link 9 through whose free end is passed a push rod or bar 10, which may be adjusted to any desired position and then firmly secured or set-screwed to the link by the screw 11. The upper end of the rod 10 is pivotally secured in any desired manner to the short arm of a vertically oscillating lever 12 fulcrumed at the upper terminal of a post or staff 13 which is secured in any adjusted position to a bracket 14 leading from the plate 1. The free end of the long arm of the lever 12 is provided with an elongated slot s along which is secured an adjustable bracket or bearing 15 supporting the fixed end of a laterally projecting horizontal rod or arm 16 from which is freely hung or suspended the drop-shield 17, said shield or cut-off being mounted to come in the path of the rays r, r, issuing from the hood B of the projecting lantern L, when dropped to its lowest position, thereby intercepting the rays before they can do any harm to the film a under circumstances such as above related.

Secured to the plate 1 and maintained apart by insulating material are the stationary wipers or contacts 18, the lobe 19 of one of the wipers connecting directly to the wire w. To the under side of the link-supporting arm of the bracket 4 is secured a plate 20 (properly insulated) terminating at one end in a wiper or contact 21 adapted to play between and along the inner faces of the spring contacts 18, the opposite end of the plate 20 being provided with a lobe or loop 22 to which the wire w' is secured, it being understood that the wires w, w', form the circuit wires for the current fed to the motor M by which the film is advanced.

The operation of the device is apparent from the drawings, but may be briefly described as follows: When the machine is in service and the film maintained taut or under tension in its passage from the reel of one magazine to that of the other, the spool 7 bearing against the film under the action of the weighted arm 5 leading from the oscillating bracket 4, sustains the arm in a raised position, the link-supporting leg of the bracket 4 being depressed, and the push rod 10 pulled down so as to hold the long arm of the lever 12 elevated, and the drop-shield 17 raised above the path of the rays r, r, the rays being thereby left free to pass to the film through the usual window t, as well understood in the art. In the event however, that anything happens to the film so as to release the tension imposed thereon (for example a break in the film), the film being no longer under tension will release the spool 7, allowing the lever or arm 5 to drop, whereupon the depressed end of the angle-bracket 4 to which the arm is coupled, is raised or oscillated upward, thereby lifting through the slot e the spindle 6 supporting the spool 7 (the plate 8 oscillating with the spindle 6 about the axis of the spindle or bolt 2 and keeping the slot permanently covered), and pushing upward the rod 10, the latter in turn forcing down the long arm of the lever 12 and dropping the shield 17 across the path of the light rays. The rays are thus automatically cut off from the film; and in the event the operator is not on hand to stop the motion head, the film is at least safe from any injury by fire as the heat from the rays can no longer reach the film. At the same time that the shield 17 is dropped into position across the rays r, r, it will be observed that the raised end of the bracket 4 has withdrawn the wiper 21 from contact with the wipers 18, so that the motor circuit is broken causing the motor M and motion head to come to a stop and thus arresting further advance of the film. As soon as the film has been restored and the accident remedied the parts are reset.

Since the parts 4 and 5 operate as a unit, they may for convenience be jointly considered as a tripping lever the long arm of which is weighted and the short arm carrying the spindle 6 on which the spool 7 is supported. The lever may be considered as fulcrumed about the axis of the bolt or fulcrum spindle 2 on which the spool 3 is mounted. It will be observed that in the operation of the device the free or oscillating end of the short arm of the lever 12 describes an arc curved in the opposite direction from the arc described by the free end of the short arm of the tripping lever or the oscillating end of the bracket 4 carrying the spindle 6. Since the push rod 10 has its opposite ends coupled to the oscillating terminals of these respective members, it is apparent that without the provision of the oscillating link 9 the parts would

bind and would not permit the rod 10 to maintain a permanently vertical position. It is for this reason that the link 9 is employed in the construction here shown. The 5 device may be changed in many particulars without departing from the nature or spirit of the invention. Features shown but not alluded to are well known in the art and require no description in the present connection.

Having described my invention what I claim is:

1. In a motion picture projecting machine, a traveling film maintained under tension, a light source, means for conducting the rays to the film, a fixed support, a vertically oscillating weighted lever fulcrumed about a fixed spindle on said support, a guide spool on said fulcrum spindle, a spindle secured 15 to the free end of the short arm of the weighted lever in proximity to the fulcrum spindle, a sprocket spool on the last named spindle, an arm on the weighted lever positioned opposite the spindle carrying the 20 sprocket spool, a link block pivotally coupled to the free end of the arm aforesaid, a post, a vertically oscillating lever fulcrumed to said post and provided with a short and long arm, a push rod pivotally connected to 25 the short arm of said lever and connected to the link block aforesaid, a rod projecting laterally from the long arm of the lever, and a shield suspended from the rod aforesaid, and adapted to be dropped across the light 30 rays upon a release of the weighted lever by the film due to a removal or reduction in the normal tension imposed on the film, the parts operating substantially as, and for the purpose set forth.
2. In combination with a magazine of a motion picture projecting machine, a weighted tripping lever mounted on the outer wall of the magazine, a fulcrum spindle for the lever projecting into the magazine, a guide spool or roller for the film mounted on the spindle, a second spindle leading from the short arm of the tripping lever through a slot in the wall of the magazine, a sprocket 45 spool on said second spindle engaging the film, the latter being sufficiently taut to 50 maintain the weighted arm of the tripping lever elevated, and the short arm carrying the sprocket spool depressed, a source of light, a drop-shield, intermediate connections between the tripping lever and drop shield operating to force the shield across the path of the light rays coming from the light source upon a release of the tripping lever due to a removal or reduction of the normal tension imposed on the film, and a 55 shutter or cover plate opposite the slot in the wall of the magazine, traversed by the fulcrum and oscillating spool-supporting spindles leading from the tripping lever, the shutter being free to oscillate with the spindle supporting the sprocket spool, about the axis of the fulcrum spindle.
3. In a motion picture projecting machine, a traveling film maintained under tension, a light source, means for conducting the 60 rays to the film, a fixed support, a vertically oscillating weighted lever fulcrumed about a fixed spindle on said support, a spindle secured to the free end of the short arm of the weighted lever in proximity to the fulcrum spindle, a sprocket spool on the last 65 named spindle, an arm on the weighted lever positioned opposite the spindle carrying the sprocket spool, a link block pivotally coupled to the free end of the arm aforesaid, a 70 post, a vertically oscillating lever fulcrumed to said post and provided with a short and long arm, a push rod pivotally connected to the short arm of said lever and connected to the link block aforesaid, a rod projecting laterally from the long arm of the lever, and a 75 shield suspended from the rod aforesaid, and adapted to be dropped across the light rays upon a release of the weighted lever by the 80 film due to a removal or reduction in the normal tension imposed on the film, the parts operating substantially as, and for the purpose set forth.

In testimony whereof I affix my signature, in presence of two witnesses.
